UNITED STATES PATENT OFFICE.

GUSTAV EGLOFF, OF INDEPENDENCE, KANSAS, ASSIGNOR TO UNIVERSAL OIL PRODUCTS COMPANY, OF CHICAGO, ILLINOIS, A CORPORATION OF SOUTH DAKOTA.

PROCESS AND APPARATUS FOR TREATING HYDROCARBONS.

Application filed January 14, 1920, Serial No. 351,281. Renewed January 11, 1928.

This invention relates to improvements in process of treating hydrocarbons and refers more particularly to a process of converting relatively high boiling point hydrocarbons into those of lower boiling points.

Among the salient objects of the invention, are to provide a process in which the vapors are superheated to increase the cracking prior to their being subjected to reflux condensation so as to facilitate reactions of the process and limit, as far as is practical the extent of the dephlegmation or reflux condensation. It is well known that in cracking processes now in commercial use that very considerable reflux condensation takes place with consequent loss of heat units during the cracking of oil. The present invention reduces this reflux condensation to a very considerable extent.

In order to more clearly understand the invention, I have shown the accompanying drawing in which the single figure is a somewhat diagrammatic plan view with parts in section of a novel form of apparatus useful for carrying out the process.

Referring to the drawings, 1 designates the furnace in which is mounted a shell still 2. This still 2 is provided with usual manholes 3 and 4, liquid residue draw-off 5 controlled by throttle valve 6. The vapors pass out through goose-neck or vapor line 7 into a header 8. This header 8 is connected to a second header 9 by means of a plurality of relatively small tubes 10 which lie in the oil in the bottom of the lower part of the still. The arrangement is such that these tubes can be readily cleaned or replaced when desired. The header 9 is connected by pipe or conduit 11 to a dephlegmator 12. The heavier vapors which condense in the dephlegmator are returned by the reflux line 13 into the still at a point below the liquid level of the latter as shown at 14. The vapors which do not condense in the dephlegmator pass by line 15 to water condenser 16 which is in turn connected by pipe 17 to receiver 18. The latter is provided with liquid draw off 19 controlled by valve 20 and gas outlet 21 controlled by valve 22. If desired, a throttle valve 23 may be interposed at the upper end of the dephlegmator 12. A valve 24 may be interposed in line 7 and valve 25 in line 13. The process can be carried out by distilling and condensing under a uniform pressure of say 100 pounds

with an oil temperature in the still of 750° F. The temperature in the lower end of the still, of course, will be hotter than the upper end. If desired, a differential pressure may be maintained on the apparatus by suitably regulating the valves. Passing the vapors through the pipe 10 will of course superheat them and tend to increase the cracking of the constituents thereof. Accordingly less reflux condensation of the insufficiently cracked heavier vapors will be required. As far as I know in addition to the process being novel, the apparatus herein described is also novel.

I claim as my invention:

1. A process of converting relatively high boiling point hydrocarbons into those of lower boiling point, consisting in heating the oil in the still under vapor pressure, taking off vapors, therefrom, passing such vapors in relatively small separated streams through the lower portion of the still out of contact with the main body of oil in the still, subjecting the superheated vapors to a reflux condensing action and returning such reflux condensate to the body of oil in the still.

2. A process of converting relatively high boiling point hydrocarbons into those of lower boiling point, consisting in heating the oil in the still under vapor pressure, taking off vapors therefrom, passing such vapors through the lower portion of the still out of contact with the main body of oil in the still, subjecting the superheated vapors to a reflux condensing action and returning such reflux condensate to the body of oil in the still.

3. The process of converting relatively high boiling point hydrocarbons into those of lower boiling point, comprising introducing oil to a still, in subjecting the same to heat while in the still and under vapor pressure, in removing vapors therefrom, and then directly passing the vapors in small streams through the body of oil in the still out of contact with the oil therein to superheat the vapors without converting them into fixed gases, in passing the vapors through a reflux condenser, in returning the reflux condensate to the still, and in discharging vapors from the reflux condenser to a condenser for condensation and collecting them.

4. An apparatus for cracking hydrocar-

bons, comprising a furnace, a still mounted therein, a vapor line leading from the still, a plurality of small horizontal pipes passing through the lower portion of the still, 5 means for discharging vapors from the vapor line into said pipes to pass through the still, means for collecting the superheated vapors after passage through said pipes, a reflux condenser into which said vapors are introduced, means for discharging the vapors from the reflux condenser, and means 10 for discharging the reflux condensate into the still.

GUSTAV EGLOFF.
